UNITED STATES PATENT OFFICE.

MARY J. McARTHUR, OF CLEVELAND, OHIO.

WINDOW BOX.

Application filed March 21, 1924. Serial No. 700,902.

To all whom it may concern:

Be it known that I, MARY J. McARTHUR, a citizen of the United States of America, and a resident of Cleveland, in the county of Cuyahoga and State of Ohio, have invented a new and Improved Window Box, of which the following is a description.

My invention relates to a window box for holding foods and particularly relates to a box adapted to be placed at the interior of a window at an opening provided by partially raising the lower sash.

The general object of my invention is to provide a window box of greatly simplified construction and embodying novel means of a simple character to effect a tight closure of the window opening to prevent drafts into the room yet providing ample ventilation to the interior of the box.

20 The nature of the invention and its distinctive features and advantages will clearly appear as the description proceeds.

Reference is to be had to the accompanying drawings forming a part of this specification, it being understood that the drawings are merely illustrative of one example of the invention.

Figure 1 is a perspective view of my improved box emplaced in a window;

30 Figure 2 is an enlarged transverse vertical section in the plane of the line 2—2 in Figure 1;

Figure 3 is a horizontal section on an enlarged scale in a plane indicated by the line 3—3, Figure 1;

35 Figure 4 is a detail in vertical section at the rear upper corner of the box;

Figure 5 is a detail in vertical section at the lower rear corner of the box;

40 Figure 6 is a perspective view of a portion of a window given to show the manner of closing the opening at the top of the lower sash when said sash is raised to afford ventilation of the box;

45 Figure 7 is a detail in transverse vertical section in a plane indicated by the line 7—7, Figure 6.

In carrying out my invention in accordance with the illustrated example, an oblong box 10 is provided, the back 11 of which is formed of wire mesh or equivalent open material to afford ventilation through the window to the interior of the box. The front of the box is closed in the illustrated example by a drop cover 12 hinged to the bottom of the box body. The numeral 13 indicates

bracket bars suitably secured to the window sill B as by screws 14 and the numeral 15 indicates pins provided on the bottom of the box 10 and depending therefrom to enter 60 corresponding holes in the bracket bars 13 at the outer ends.

The box 10 is positioned adjacent to one side of the window frame A but usually is not of sufficient length to extend to the opposite side of the window frame. Hence, it becomes necessary to provide a closure for the window below the sash a at one end of the box 10 for which purpose I provide a slide 16 on the body 10 at the back. Said 70 slide 16 has at the lower edge a forwardly directed right angular flange 17. The lower edge of the slide 16 with its flange 17 is held and guided by a guide strip 18 having an upturned free edge 19 at the back of slide 16, 75 the front edge of the strip 18 being soldered or otherwise suitably fixed to the bottom of the box body 10 at the under side. At the top the slide 16 has a channel 20 formed thereon which is accommodated beneath and 80 guided by a guide strip 21 soldered or otherwise fastened at its front edge to the top of the box 10 and forming with the top of the box body a groove to receive the channel 20 of the slide 16. The slide 16 may be slid to 85 form a closure completely over the box 10 or may be slid to an extended position projecting beyond the box 10 as shown in Figures 1 and 2 to close the opening beneath the sash 90 c at that side of the box 10, the strips 18 and 21 guiding said slide 16 in its movements.

It becomes necessary with the box 10 emplaced at the opening presented by the raising of the sash a to effect a closure between the sash a and the box for which purpose I 95 employ a weather strip 22. Said weather strip 22 is accommodated at its front edge both by the channel 20 and the groove formed by the strip 21. The strip 22 fits snugly in the channel 20 and with the slide 100 16 extended beyond the box 10 the strip 22 is partially accommodated in the groove formed by the strip 21. In this connection it will be obvious that the weather strip 22 being the width of the window and the strip 16 only the width of the box and thus less than the width of the window, that the end of the strip 22 opposite to the projected end of the slide 16 would have no support or partial housing when the slide 16 is in 110 the projected position; hence, the groove presented beneath the strips 21 on the box

accommodates that portion of the strip 22 which is not engaged by the channel 20 of the slide 16. Said weather strip 22 has cut-outs or rabbets at the ends thereof to conform to the side rails of the sash *a*, so that the weather strip will contact closely with the glass in said sash and a tight closure will therefore be effected at the top of the box 10 and beyond the box at the upper edge of the slide 16. It will be clear that a complete closure of the opening below the sash *a* is effected with the box 10 in position by the extension of the slide 16 and the weather strip 22.

15 The raising of the lower sash *a* leaves an opening between the upper and lower sashes at the top of the upper sash and to prevent drafts at said opening I provide a weather strip 23 usually formed of rubber as is the weather strip 22. Said strip 23 has cut-outs at the ends to conform it to the sash and window frame members and to effect an edge contact with the planes of the upper sash when said strip 23 is tacked or otherwise fastened at its outer edge to the meeting rail of the lower sash *a*.

I would state in conclusion that while the illustrated example constitutes a practical embodiment of my invention, I do not limit myself strictly to the exact details herein illustrated, since, manifestly, the same can be considerably varied without departure from the spirit of the invention as defined in the appended claims.

35 Having thus described my invention, I claim:

1. A window box adapted to be disposed at an opening provided by raising the lower sash of the window, a vertically disposed slide at the back of the box and adapted to be projected beyond an end thereof, guide members at the top and bottom of the box for said slide, and a weather strip held at

its forward edge by said slide at the top of the latter, said weather strip being accommodated at one end by the channel on said slide and throughout the remainder of its length by said guide members at the top of said box. 45

2. A window box adapted to be disposed at an opening provided by raising the lower sash, a vertically disposed slide at the back of said box adapted to be projected beyond an end thereof, a channel on said slide at the upper edge, guide means on the box for said channel, and a weather strip held in said channel and extending rearwardly beyond the plane of the slide; together with a strip on the box at the top forming a groove for said channel, said weather strip 80 being accommodated at one end by the channel on said slide and throughout the remainder of its length by said guide members at the top of said box. 55

3. A window box adapted to be disposed at an opening provided by raising the lower sash of the window, a vertically disposed slide at the back of the box and adapted to be projected beyond an end thereof, said slide having the lower edge thereof directed forwardly in the form of an approximately right angular flange extending beneath the bottom of the box, a strip on the box at the side of the bottom, said strip being spaced from the bottom of the box to accommodate the lower edge of said slide and the flange thereof, a guide strip on the box at the top forming a groove between said strip and the top of the box, said groove opening rearwardly, a channel on the slide 80 at the top and fitting said groove, and a weather strip held in said channel, said weather strip projecting beyond the plane of the slide and adapted to make close contact with the lower window sash. 75

MARY J. McARTHUR.
